Primary Examiner — Christian P. McLean
Assistant Examiner — Sara S Sahneh

(57) **CLAIM**

The ornamental design for a combined movement and presence sensor as shown and described.

DESCRIPTION

1. Combined movement and presence sensor

1.1 : Perspective

1.2 : Top

1.3 : Back

1.4 : Bottom

1.5 : Front

1.6 : Left

1.7 : Right

Designation of the design: new combined movement and presence sensor; Use of the design: it is used as a combined movement and presence sensor; Characteristics of the design: the shape in its entirety; Designs that best illustrate the features of the design: reproduction 1.1 (perspective view) and reproduction 1.5 (front view).

The broken lines provided in the reproductions are shown for the purpose of illustrating portions of the combined movement and presence sensor and form no part of the claimed design.

1 Claim, 7 Drawing Sheets
